United States Patent

Des. 242,572
Patented Nov. 30, 1976

242,572

ROUND BALER MACHINE

Warren William Grist, Newton, Richard Jack Robbins,
Derby, and Gary Wayne Weddle, Wichita, Kans., as-
signors to Hesston Corporation, Hesston, Kans.

Filed June 2, 1975, Ser. No. 582,843

Term of patent 14 years

Int. Cl. D15—03

U.S. Cl. D15—27

Fig. 4.

Fig. 3.

Fig. 3.

Fig. 6.

FIG. 1 is a top, right front perspective view of a round baler machine embodying our new design;

FIG. 2 is a top, left, rear perspective view thereof;

FIG. 3 is a front perspective view thereof;

FIG. 4 is a rear perspective view thereof;

FIG. 5 is a perspective view thereof taken from the right side; and

FIG. 6 is a perspective view thereof taken from the left side.

We claim:

The ornamental design for a round baler machine, as shown.
